BOTTLE CARRIER

Alois Eberhard, Evansville, Ind., assignor of one-half to Jack A. Stone, Evansville, Ind.

Application June 11, 1952, Serial No. 292,859

6 Claims. (Cl. 294—31.2)

1

The present invention relates to bottle carriers and particularly to a carrier for use with an individual bottle.

The primary object of my invention is to provide a bottle carrier comprising a bail from which is supported a bottle-neck-engaging portion, such carrier being so constructed as to be readily and positively securable to a bottle.

A further object of the invention is to provide such a carrier which, while having the desired operational characteristics, will be constructed of a minimum number of parts and in such a manner as to render its manufacture simple and inexpensive.

Further objects will become apparent as the description proceeds.

To the accomplishment of the above and related objects, my invention may be embodied in the forms illustrated in the accompanying drawings, attention being called to the fact, however, that the drawings are illustrative only, and that change may be made in the specific constructions illustrated and described, so long as the scope of the appended claims is not violated.

Fig. 1 is a perspective view showing a preferred embodiment of my invention in an intermediate state in its manufacture;

Fig. 2 is a perspective view of the completed carrier showing the manner in which it is intended to be associated with a bottle; and

Fig. 3 is a perspective view similar to that of Fig. 2 but showing a modified form of my invention.

Referring more particularly to the drawings, it will be seen that my carrier 10 comprises basically a bottle-neck-engaging ring 11 supported from a bail 12. Means 13 is provided whereby ring 11 can be readily affixed to and removed from the bottle neck 14.

Carrier 10 is formed of two strands of wire 15 and 16 laid side by side and, as shown in Fig. 1, twisted together longitudinally throughout a part only of their lengths. This twisting is done preferably from a point 17 slightly removed from an end of the pair of wires to a point 18 relatively farther removed from the other end of said wire pair. Alternatively, the wires 15 and 16 could be twisted together at spaced intervals between points 17 and 18 or merely at the points 17 and 18 themselves. As said, however, I presently prefer to twist the wires throughout their lengths continuously from point 17 to point 18.

The ends of wires 15 and 16 nearest point 18 are turned oppositely out of the line common to the wires and back again into such line to form

2

a pair of substantially semicircular portions 20 and 21 which together constitute the resilient, open, neck-engaging ring 11. The free ends 22 and 23 are then turned substantially radially outwardly and preferably curled back on themselves to form blunted ends or finger pieces 24 and 25.

The opposite ends of wires 15 and 16 (the ends nearest point 17) are each turned outwardly and back on themselves to form hooks 26 and 27. Together the ends 22 and 23, and the hooks 26 and 27 constitute the means 13, as will later become apparent.

Strands 15 and 16 are together bent out of the plane of ring 11, substantially about their juncture with said ring at point 18, to form bail 12 spanning said ring and with the hooks 26 and 27 in juxtaposition with the ends 22 and 23. Bail 12 is so positioned that the plane of said bail substantially coincides with the median plane of ring 11. For the purpose of this specification, the "median plane of said ring" refers to that plane perpendicular to the plane of ring 11 and including the point 18, the center of said ring, and the point midway between the ends 22 and 23.

While bail 12 may be shaped in any form most convenient for the purpose for which the carrier is intended, I presently prefer to form the bail with upstanding side portions 28 and 29, and a horizontal or handle portion 30.

In attaching carrier 10 to a bottle neck, the ring 11, being open between the ends 22 and 23, may be spread to receive neck 14. Most bottles are formed with a bead 14' surrounding the opening therein, and the ring 11 is placed about the neck immediately below this bead. The end 22 is then engaged in the hook 26 and the end 23 is engaged in the hook 27, thereby locking ring 11 about neck 14. Because of the natural resiliency of strands 15 and 16, upon disengagement of the ends 22 and 23 from hooks 26 and 27, the ends will spring out, thereby greatly facilitating the removal of the carrier from the bottle.

In Fig. 3 I have shown a modified form of my invention. Instead of twisting the strands 15 and 16 between points 17 and 18, the wires may simply be laid side by side and fixed together between points 17 and 18 as by welding at spaced intervals, or by dipping the entire carrier into a bath of molten solder while holding the two halves 31 and 32 in mating relationship. Such a construction would enable the complete fabrication of the two halves 31 and 32 prior to joining them together to form the completed carrier.

While I have specifically illustrated and described my invention as a bottle carrier, it will be obvious that it is as equally adaptable and useful for carrying any type of container having an annular flange surrounding the opening therein, such as a fruit jar, flower pot, or the like, and it is not intended that the device claimed should be restricted to a use only as a bottle carrier.

I claim as my invention:

1. A bottle carrier comprising a resilient, open ring, and a bail disposed in the median plane of said ring with one end thereof fixed to said ring and the other end thereof disposed adjacent the opening in said ring, the ends of said open ring being bent substantially radially outwardly, and the last of said end of said bail being formed with a pair of hooks in which said ring ends are engageable to lock said ring about the neck of a bottle, said hooks being open for ready insertion of said ring ends by movement of said ring ends in a direction substantially parallel with the axis of said ring.

2. A bottle carrier comprising a resilient, open ring and a bail supporting said ring in a plane substantially perpendicular to the plane of said bail, said carrier being formed of two strands of wire secured together throughout a part only of their lengths, one end of each strand being bent out of the line common to said strands to form a semi-circle, such semi-circular portions of said strands constituting said resilient ring, the remaining portions of said strands being bent out of the plane of said ring substantially about their juncture with said ring to form said bail with the free ends of said strands in juxtaposition with the open ends of said ring, the extremity of each such free end being formed to provide an open hook for the ready reception of the extremity of the first-named end of one of said strands to lock said ring about the neck of a bottle.

3. The device of claim 2 in which the extremities of said first-named strand ends are bent substantially radially outwardly, and said hooks open substantially in a direction parallel with the axis of said ring.

4. A bottle carrier comprising a resilient, open ring, a bail supported on said ring in the median plane thereof, and means for releasably fixing the open ends of said ring to an end of said bail whereby said ring can be locked about the neck of a bottle, said carrier being formed of a pair of wire strands longitudinally twisted together from a point slightly removed from one end of said pair to a point relatively farther removed from the other end of said pair, the last said ends of said pair being bent oppositely out of a common line and back substantially into said common line to form said resilient ring with the open ends thereof being turned substantially radially outwardly, the opposite ends of said strands each being bent to form a hook, and the twisted portion of said strand pair being bent out of the plane of said ring substantially about the junc-

ture of said strands and said ring to form said bail with said hooked ends thereof in juxtaposition with said ring ends, said ring ends being engageable with said hooks ends whereby said ring can be locked about the neck of a bottle, said hooks being open for ready insertion of said ring ends by movement of said ring ends in a direction substantially parallel with the axis of said ring.

10 5. A bottle carrier comprising a resilient, open ring, a bail supported on said ring in the median plane thereof, and means for releasably fixing the open ends of said ring to an end of said bail whereby said ring can be locked about the neck of a bottle, said carrier being formed of a pair of wires laid side by side and welded together from a point slightly removed from one end of said pair to a point relatively farther removed from the other end of said pair, the last said ends of said pair being bent oppositely out of a common line and back substantially into said common line to form said resilient ring with the open ends thereof being turned substantially radially outwardly, the opposite ends of said strands each being bent to form a hook, and the welded portion of said strand pair being bent out of the plane of said ring substantially about the juncture of said strands and said ring to form said bail with said hooked ends thereof in juxtaposition with said ring ends, said ring ends being engageable with said hooked ends whereby said ring can be locked about the neck of a bottle, said hooks being open for ready insertion of said ring ends by movement of said ring ends in a direction substantially parallel with the axis of said ring.

20 6. A carrier for use with a container having an annular flange surrounding the opening therein, such carrier comprising a resilient, open ring and a bail supporting said ring in a plane substantially perpendicular to the plane of said bail, said carrier being formed of two strands of wire secured together throughout a part only of their lengths, one end of each strand being bent out of the line common to said strands to form a semi-circle, such semi-circular portions of said strands constituting said resilient ring, the remaining portions of said strands being bent out of the plane of said ring substantially about their juncture with said ring to form said bail with the free ends of said strands in juxtaposition with the open ends of said ring, said open ends being bent substantially radially outwardly and said free ends being bent to form laterally-open hooks in which said open ring ends can be respectively engaged to lock said ring about said container directly beneath said annular flange.
